UNITED STATES PATENT OFFICE

STUART A. WIER, OF DALLAS, TEXAS, ASSIGNOR TO TRIDEX CORPORATION, OF DALLAS, TEXAS, A CORPORATION OF DELAWARE

APPARATUS FOR CLEANING SURFACES

Application filed December 6, 1928. Serial No. 324,229.

This invention relates to new and useful improvements in apparatus for cleaning surfaces.

One object of the invention is to make certain improvements and advances over the apparatus set forth in my copending application filed February 14, 1927, Serial No. 168,161, which issued as Patent No. 1,766,088, June 24, 1930.

A particular object of the invention is to provide an atomizer in connection with solution, steam and hot water discharge pipes, whereby these fluids are all brought to a common point of admixture and caused to flow in steady streams with little or no fluctuation.

A further object of the invention is to provide means whereby steam is constantly supplied while the apparatus is operating and means for cutting off the supply of steam is eliminated, thus making the apparatus more efficient and safe to operate.

Another object of the invention is to provide a by-passing hot water supply valve, whereby a supply of hot water will be had at all times while the operator is operating and which cannot be cut off, thus assuring a dilution of the detergent solution and preventing the use of too rich a solution.

Still another object of the invention is to provide a steam coil and discharge pipe connection, whereby less impedance to the flow of steam is offered.

A still further object of the invention is to provide means for condensing or concentrating the admixture of detergent solution, steam and hot water and suddenly expanding the same, for more thoroughly admixing the fluids.

Another object of the invention is to connect the rubber or other discharge hose or conductor with the atomizer by means of a flexible metallic hose, whereby a flexible and durable joint connection is made and also whereby some of the heat will be dissipated.

A construction designed to carry out the invention will be hereinafter described, together with other features of the invention.

The invention will be more readily understood from a reading of the following specification and by reference to the accompanying

drawings, in which an example of the invention is shown, and wherein:

Fig. 1 is an elevation of an apparatus constructed in accordance with the invention,

Fig. 2 is an elevation at right angles to Fig. 1,

Fig. 3 is a view partially in elevation and partially in section of the apparatus shown in Fig. 1,

Fig. 4 is a similar view at right angles to Fig. 3,

Fig. 5 is a plan view,

Fig. 6 is a plan view of the generator,

Fig. 7 is an elevation of the same,

Fig. 8 is a partial vertical sectional view of the apparatus,

Fig. 9 is a detail showing the hot water and steam pipes reversed,

Fig. 10 is a diagrammatical view of the apparatus, and

Fig. 11 is a detail of the hot water valve showing the by-pass.

In the drawings the numeral 10 designates a vertical cylindrical metal jacket of suitable construction mounted on an annular base 11 having a plurality of draft openings 11'. A suitable fuel burner 12 is supported in the lower portion of the jacket just above the base. Any kind of fire or heating means suitable for the purpose may be employed. The jacket has a lining 13 of asbestos or equivalent material (Figs. 3 and 4) which extends from the top of the jacket to a point below the outlets of the burner.

Within the jacket is disposed a coiled steam and hot water generator unit 14. This unit includes a central vertical water column 15 closed at each end, but having a cleanout cap 15' at its top. A water inlet pipe 16 extends into the jacket and includes a controlling valve 17. For successful operation, water must be supplied at substantially the same pressure which is maintained in the generator. The pipe 16 is connected to the upper end of a vertical pre-heating coil 18 (Figs. 3, 6 and 8) and the lower end of the coil enters and supplies water to the lower end of the column 15.

The pre-heated water rises in the column 15 and supplies warm water to the lower ends

of circulating coils 19, of which I have shown five. The circulating coils have their lower ends connected to the lower end of the column 15 while their upper ends are connected to the upper end of said column.

5 Water flows from the column into the lower ends of the circulating coils and is vaporized and converted into steam in the upper portions of said coils, whereby steam is discharged into the top of the column. It is obvious that such steam is saturated or wet. If sufficient water is supplied the coils 19 will contain only water and thus hot water and hot steam would be discharged into 10 the top of the column 15.

A pair of steam coils 20 are connected at their upper ends to the upper end of the column 15 so as to receive saturated steam or hot water from said column. The lower ends 20 of these coils are secured in a Y-coupling 21 whereby both steam coils may be connected to a common steam discharge pipe 22 leading through the side of the jacket. A hot water discharge pipe 23 leads from the bottom 25 of the column through the jacket 10 of the device. An overflow pipe 24 extends from the top of the column 15 through the top of the jacket 10. The pipes 22 and 23 extend through an escutcheon casting 23', 30 thus forming a tight joint with the jacket 10.

A pickup pipe 25 extends down into the column 15 and has its upper end connected to a discharge pipe 26 which extends from the top of the column through the side of the 35 jacket and connects with a branch discharge pipe 27 by means of a T 28. A pressure gage 29 is connected with the T. A combination check and cut-off valve 30 is connected in the pipe 27. Valves of this character may 40 be purchased in the open market and are arranged so that when open fluid may flow through the pipe 27 past the valve, but liquid cannot flow back into said pipe 27. The valve may be closed to prevent the flow of 45 liquid in either direction.

The various pipes maintain the generator, which latter is composed of the coils and the water column, in position in the jacket, but if desired additional fastenings may be supplied. It is preferable to arrange the burner 50 12 so that the flame will be directed upwardly through the coils and around the column 15. This provides for a direct heating of the coils as well as those portions of the pipes 55 22 and 23 in the path of said flames. A conical cover 31' is mounted on the top of the jacket and has a central collar 32' for connecting with a chimney if desired. The cover 31' may have a slip connection with the 60 jacket so as to be readily removed if desired.

The pipe 27 is extended into the upper portion of a detergent tank 31, which is suitably fastened to the upper portion of the jacket, as by brackets 32. It is important 65 that the tank be rigidly attached and it is

desirable that it be close to the jacket so as to provide a compact structure. A cap 34' is screwed into the top of the tank and may be removed for introducing soap or any other detergent, such as liquid hydrocarbons of kerosene type, washing powders, caustic alkali and the like. A relief cock 33 is connected to the upper end of the tank and when it is desired to recharge said tank the valve 30 may be closed and the cock opened, whereby pressure within the tank is released. The pipe 27 is terminated near the bottom of the tank so as to deliver the hot fluid at the bottom of the charge, thus agitating and heating the charge when said fluid rises in the 80 tank. A cleanout plug 34 is secured in the bottom of the tank.

The pickup pipe 25 may vary in length. If it is desired to deliver hot water to the tank 31, then the pipe 25 must extend low 85 enough in the column to be constantly immersed in water; but if it is desired to deliver saturated steam to said tank, then the lower end of the pipe 25 should not be immersed in water. It is obvious that the height at which 90 the water stands in the column 15 will depend largely upon the amount of water supplied to the generator and the pressure within the same. As there is considerable variation in this step of the method, it is obvious that the 95 hot fluid supplied to the tank may either be a liquid or saturated steam.

The solution which flows from the tank 31 will be, of course, hot and its character will depend upon the particular detergent 100 used. A solution discharge pipe 35 is connected at its upper end with a hand valve 36, which in turn is connected into the side of the tank 31 just above the bowl bottom thereof. This arrangement permits sediment and 105 foreign matter to settle in the bottom of the tank without being drawn off through said valve. The lower end of the discharge pipe 35 is suitably connected with the upper end of an atomized body 37. This atomizer forms 110 the subject matter of a separate application filed by Charles S. Crickmer, May 5, 1928, Serial No. 275,355, and, therefore, will only be described in a general way.

The steam pipe 22 is connected to a branch 115 22' (Fig. 2) which in turn is connected to the upper end of the atomizer body 37. There is no valve in either of these pipes and, therefore, the steam from the coils may pass directly into the atomizer. The hot water pipe 23 is connected with a valve 38 which is connected at one side with the atomizer below the pipe 22. The hot water valve has a by-pass port 38', as is shown in Fig. 11, that when said valve is moved to its fully closed position, a small water passage will be left open. The operator is prevented by this arrangement from entirely cutting off the supply of hot water and thus obviating too rich 120 a detergent mixture.

The hot detergent solution flowing by gravity in a body is discharged into the atomizer where it is impelled downwardly by the steam and diluted by the hot water.

5 The pipe 35 is connected to the atomizer body by a union 35'. The solution is delivered to a jet 22a extending into a nozzle 23a within the body 37. The steam enters around the jet, while the hot water enters around the nozzle, the entrances being separated by the nozzle. The nozzle discharges into the bowl bottom of the body which has an orifice 39' through which the fluids are discharged into the bowl 39. The introduction of the hot 10 water is very important for the reason that an over-rich detergent solution may be formed in the tank 31 and diluted to the proper consistency by the hot water from the pipe 23. This enables the operator to use 15 the machine for a longer period without replenishing the detergent. The introduction of the hot water also has a tendency to reduce the temperature of the steam, but without reducing its velocity.

20 25 The three fluids, that is the solution, steam and hot water, are admixed in the atomizer body which forms a common point and it is obvious that it makes little difference whether the steam pipes and the hot water 30 pipes are connected as shown in Figs. 1, 2, 3 and 5, or if the connection is reversed, as is shown in Fig. 9, where the hot water pipe is connected to the body 37 above the steam pipe 22'. The function of the steam is to 35 impel the solution so as to conduct it to its point of discharge and while it is desirable to have sufficient velocity it is undesirable to have high temperature, which will be herein-after referred to.

40 45 The fluids are compressed in the lower end of the body 37 and are discharged through the orifice 39' into the bowl 39 in which the fluids are suddenly expanded before final discharge from the atomizer. This bowl is connected with a discharge nipple 40, but the bowl could be eliminated and the nipple or any other discharge connection applied direct to the body. The nipple is connected with a section of flexible metallic hose 41, 50 which in turn is connected with a length of ordinary rubber or other similar hose capable of conducting a hot fluid. The hose 42 may be of any practical length and is connected at its discharge end with a nozzle 43 having a handle 44. The nozzle 43 may have 55 a head 45 of any suitable construction designed to discharge the fluid in a finely atomized spray, it being desirable to avoid a solid stream, although the head may be adjustable to emit a solid stream when it is desired to discharge water for washing purposes.

60 The parts 40, 41, 42 and 43 constitute a fluid discharge conductor and, of course, may vary in construction. An advantage in em-

ploying the metallic hose section 41 is that the same will absorb and dissipate some of the heat of the flowing fluid, as well as permitting universal movement without breaking or leaking.

In general the operation is carried out by supplying water from the pipe 17 to the coil 18, whereby the temperature is raised and the water pre-heated. This water is discharged into the bottom of the column 15 and enters the circulating coils 19 in which it rises. If a limited amount of water is supplied, saturated steam will be generated in said coils 19 and discharged into the upper end of the column 15. If a large amount of water is supplied, hot water and not steam may be discharged into the column 15. If the lower end of the pickup pipe 25 is immersed in water, hot water will be forced through said pipe, owing to the pressure within the generator, or if it is not immersed saturated steam will flow up through said pipe. The hot fluid from the pipe 25 will be conducted by the pipes 26 and 27 into the tank 31.

The tank 31 having been previously charged with a suitable detergent, the hot fluid upon entering said tank will agitate, dissolve and heat the detergent, as the case may be, and thus form a hot detergent solution. This solution will flow out through the pipe 36 to the atomizer 37. Saturated steam or very hot water entering the upper ends of the coils 20 from the column 15 will either be reheated or converted into steam, and as this steam is discharged from the lower ends of the coils and passes into the pipe 22 it will be subjected to the intense heat of the flame of the burner 12.

Owing to the small diameter of the pipe 22, as well as the steam coils, it is obvious that a fairly high pressure will be built up. This pressure will be exerted throughout the generator, against the inflowing water and within the tank 31, so that the liquid solution will be free to flow by gravity. The pressure built up may, as an example, be held at seventy (70) pounds per square inch by providing a pop-off valve 24' in connection with the overflow pipe 24, which can be set at this pressure or any other desired pressure.

I wish to make it clear and it is very important in this operation that the steam be quickly generated and flow unimpeded to its work, because the major function of the steam is to furnish pressure for impelling the solution to the work and, therefore, its temperature is unimportant. It is not the purpose of the theory of this invention to employ steam for cleaning purposes. The aim is to obtain velocity rather than temperature.

The hot detergent solution delivered to the body 37 is admixed with hot water introduced by the pipe 23 and the diluted hot solution is conducted by the parts 41, 42 and 43

to the head 45 from which it is sprayed on the work.

If good hard soap of a quality equal to ordinary toilet soap is used, the most delicate surfaces and material, capable of being washed, may be cleaned with the spray produced by this method and without injury. This is due to the fact that while the detergent solution may have a temperature ranging from 150 degrees Fahrenheit to 200 degrees Fahrenheit, and the hot water from pipe 23 may have a like temperature, and the steam or gaseous fluid may have even a higher temperature, the higher temperature of the steam or gaseous fluid is reduced during the travel of the solution to the nozzle 43 and is dissipated in the spray before reaching the work. Also, there is not sufficient caustic alkali in the spray to harm the work. However, if it is desired to remove paint and varnish, then instead of toilet soap, a strong washing powder or caustic alkali compound is used.

It is quite important that a generous supply of hot fluid, either water or steam, be delivered to the tank 31 in order to produce a relatively large quantity of detergent solution. In my United States Patent No. 1,607,034, the streams of saturated steam supplied both to the detergent tank and the super-heating coil were substantially equal, and in developing the apparatus and evolving the present method I found it highly advantageous to produce considerably more liquid for the tank than for the steam coils.

The steam which is conducted through the pipe 22, being by reason of its velocity, chiefly for the purpose of impelling the detergent solution flowing from pipe 41 and the hot water flowing from the pipe 23, such steam need not be in such quantity as either the solution or the water. I have found that it is undesirable, unless paint is being removed, to have high pressure steam or high temperature steam in the spray which flows from the nozzle, but a goodly quantity of hot liquid is most desirable, provided it is atomized and is not hot enough to injure a painted surface.

It is pointed out that in this apparatus steam is constantly supplied to the atomizer and no valve is provided, thus guarding against any chance of impeding the flow of said steam. The atomization of the fluids is highly important because it prevents fluxation throughout the system and causes a steady and regular flow.

While I have described the use of water and steam and have illustrated an apparatus for using such fluids, it is clearly within the scope of the invention to use any suitable liquid or to employ any impelling fluid found practical and to, of course, use an apparatus suitable for the purpose.

What I claim is:

In a surface cleaning apparatus, a generator having a preheating element therein for producing hot fluids, a detergent solution tank, a pipe for conveying one of the fluids from the generators to the tank the length of the said pipe determining which of the fluids is conveyed to the tank, a discharge pipe leading from the tank for conducting a detergent solution therefrom, a steam pipe leading from the generator, a hot water pipe leading from the generator, a flexible metallic hose connected in common with the steam pipe, hot water and discharge pipes, a flexible conductor leading from the metallic hose, and a nozzle on the end of the conductor, the detergent solution being diluted by the hot water and impelled through the flexible hose, conductor and nozzle by the steam, the metallic hose acting to dissipate some of the heat of the fluids.

In testimony whereof I affix my signature.
